PANORAMIC SIGHTING-TELESCOPE FOR GUNS.

1,089,480.

Specification of Letters Patent.

Patented Mar. 10, 1914.

Application filed October 7, 1909. Serial No. 521,615.

To all whom it may concern:

Be it known that I, HEINRICH KORRODI, a citizen of Switzerland, and a resident of Alfredstrasse 22, Essen-on-the-Ruhr, Germany, have invented certain new and useful Improvements in Panoramic Sighting-Telescopes for Guns, of which the following is a specification.

The invention pertains to a gun sight provided with a telescope having a level in its field of sight. In known devices of this kind, telescopes are employed whose ocular and objective housings are rigidly connected together. When telescopes of this kind are used in sighting devices, wherein, as is customary, the telescope is laterally movable as regards the parts that are set in elevating the sight, the level would partake of any lateral movement of the telescope. If the angular position of the level does not change as regards the sight-carrier when the sight line is shifted laterally, the setting of the sight, with the assistance of the level, will then be absolutely correct under all conditions; whether a transverse level, for eliminating the influence of the inclined position of the wheels, or a longitudinal level for use in connection with the elevating of the sight is under consideration. Should this condition (of keeping the angular position of the level unchanged as regards the sight-carrier) not be fulfilled, the sight setting with the assistance of the level will be inadequate. The level would be perfectly useless if, for instance, the telescope were turned 90° out of its central position.

The purpose of the present invention is to provide a gun sight of the kind referred to above which shall be free from this error. This object is attained in the present invention, by using a panoramic telescope for sighting.

In the drawing is shown one embodiment of the subject matter of the invention, in which—

Figure 1 is a side view partly in section, of a sight provided with a panoramic telescope and the gun parts adjacent thereto; Fig. 2 is a longitudinal section through the panoramic telescope; Fig. 3 is a section along the line 3—3 in Fig. 2; and Fig. 4 is a longitudinal section through the housing of the ocular of a panoramic telescope of somewhat different design.

The sight is carried by an arm D secured

to one of the two gun trunnions, the sight sleeve E is pivoted by means of a stud e¹ on the said arm D and provided with a rib (rail) e² concentrically curved around the axis of this stud. The sleeve E supports the elevating arc H, which carries the panoramic telescope. The axis of the stud e¹ is parallel to the axis of the gun barrel. The rib e² is provided with gear teeth which are in mesh with the worm F. This well known oscillating arrangement of the sight-sleeve makes it possible, when combined with the level C of the panoramic sight, to eliminate the influence of the inclined position of the wheels. The spiral gear K journaled in the sleeve E, provided with a hand wheel k¹, engages the dentation h¹ on the elevating arc H and serves to set the arc in the desired elevation.

In the vicinity of the focal plane of the objective lens of the panoramic sight, the principle of which being already known, needs no explanation, a glass plate A (cross-hair plate) is inserted having a sighting line a¹ (Fig. 3) inscribed thereon. This plate has on its side nearest to the ocular, a beveled surface a² of 45° against the axial plane of the telescope. A tube-level C, with its axis perpendicular to the axis of the ocular, is located in the central plane of the glass plate A and secured on the housing B of the ocular below said plate A. On its lower side the housing of the level is provided with a window c¹. The image of the level is reflected by the surface a² in the field of view of the telescope so that the level and the sighting mark are visible at the same time.

The embodiment of the panoramic telescope shown in Fig. 4 differs from that shown in Figs. 2 and 3, merely in employing a box-level C² instead of the tube level C. The additional movement of the air bubble in the direction of the ocular, renders necessary an enlargement of the reflecting surface a² in the same direction, or, in other words, the employment of a thicker cross-hair plate A.

The ocular retains its angular position as regards the elevating arc H in setting the sight with the lateral gear, the objective reflector only being turned. As a consequence, the level C, Fig. 1, (the rectifying level for the wheel inclination) retains always the same correct position relative to the elevat-

ing arc H, irrespective of what position laterally the line of sight might be in; the influence of the inclined position of the wheels being therefore under all circumstances entirely eliminated.

If a panoramic sighting telescope with a box-level were employed as in Fig. 4, the influence of the inclined position of the wheels can be eliminated without error and 10 at the same time, the correct elevation of the gun barrel can be attained under all circumstances.

I claim:—

- 15 1. A gun sighting device comprising a panoramic telescope having a housing, an ocular, a D-shaped cross-hair-plate mounted in the housing, a horizontal plane through the axis of the ocular dividing the cross-hair-plate into an upper semi-circular and lower rectangular part and the rectangular part of said cross-hair-plate being provided with a beveled surface on the side toward the ocular and in the field of view of the telescope; and a level mounted transversely 20 to the axis of the ocular in the housing near said beveled surface and with its middle point substantially in the middle vertical plane of said cross-hair plate whereby the level will be reflected by said beveled surface into the field of view of the telescope, 25 near the lower edge of the ocular.

2. A gun sighting device comprising a panoramic telescope having an ocular, a revolving reflector and an objective whose axis coincides with the revolving axis of the reflector and intersects the axis of the ocular, a D-shaped cross-hair plate substantially having a semi-circular top part and a rectangular lower part interposed in the focal plane of the objective, the bottom straight edge beveled to an angle of 45° on the rectangular part of the cross-hair plate, a tube level mounted in a non-revolving part at right angles to the axis of the ocular in the plane of the cross-hair plate and parallel to the beveled edge thereof, a window in the housing on the outer side of said level to admit light through the level and at right angles to the axis of the ocular, co-operative relationship between said level and the beveled edge of the cross-hair plate to reflect the image of the level with precision into the field of view of the telescope near the lower edge of the ocular.

The foregoing specification signed at Bar- 55 men, Germany, this 24th day of September, 1909.

HEINRICH KORRODI. [L.S.]
